APPARATUS FOR REPRODUCING RADIO BROADCASTS OR RECORDED AUDIO FREQUENCIES

Application filed December 15, 1930. Serial No. 502,398.

This invention relates to radio receiving sets adapted both for reproducing radio broadcast programs, or the recorded audio frequencies of phonographic records. When receiving radio frequencies from the air it is usual to use one or more stages of radio-frequency amplification, a detector and one or more stages of audio-frequency amplification, but when audio frequencies from a record are to be reproduced one or more stages of radio-frequency amplification are cut out. Such sets generally employ a tuning condenser in each stage of radio-frequency amplification and the detector stage. Ordinarily when such a set is to be used for reproducing audio frequencies controlled by a phonographic record the connecting wires from such an audio-frequency circuit are plugged into the grid circuit of a tube close to the output end of the set, thus cutting out one or more stages of radio-frequency amplification. At the same time the common practice is to open the grid circuit of the detector or of one or more of the radio-frequency stages which removes the corresponding condenser or condensers from the circuit or circuits.

With our new arrangement we retain the variable condenser across the input circuit of the tube when such tube is connected with the audio-frequency source for phonographic reproduction, which condenser forms a variable capacitative reactance across the circuit. Also we retain in their respective grid circuits the tuning condensers of any stage of amplification between the point at which the leads hereinbefore referred to and the output end of the set. We have found that by adjusting the condenser (or condensers) referred to that control is secured of the ratio of reproduction of higher audio frequencies as compared with the lower audio frequencies and tone control of the reproduction of phonographic records is thus obtained. When the condenser (or condensers) is set to give maximum capacitance the attenuation of the high audio frequencies is greatest and when the condenser (or condensers) is set to give minimum capacitance the attenuation of the higher audio frequency is least.

The invention is illustrated in the draw-

ing which is a diagram of part of a reproducer circuit in accordance with our invention.

1 and 2 are tubes, the plate of one being coupled with the grid of the second tube by the transformer 3. The plate of the tube 2 may be connected with a succeeding amplifier tube or a loud speaker. The grid circuit of the tube 2 is shunted by the variable condenser C which ordinarily forms one of a gang of tuning condensers for the different stages of radio-frequency amplification and detector stage. With the grid circuit of the tube 2 are connected wires 4 through which audio-frequency electrical impulses may be fed to the grid circuit. A switch S serves to break the normal grid circuit when phonographic records are to be reproduced, but the connections of the condenser C remain unchanged. Thus when the switch S is closed and the set is reproducing radio frequencies the condenser (or condensers) serves to tune the circuit across which it is connected and when the switch is open and audio frequencies are being reproduced it serves as a tone control to accentuate high or low frequencies of the reproduction as may be desired.

What we claim as our invention is:

1. A radio receiving set including two vacuum tubes and a transformer coupling the plate circuit of one tube with the grid circuit of a succeeding tube; means for connecting the secondary circuit of the transformer with an audio-frequency circuit; a switch for opening the normal secondary circuit; and a variable condenser permanently shunting the grid circuit of the said succeeding tube, serving when the switch is closed to tune the grid circuit and when the switch is open as a tone control.

2. In a radio receiving set the combination of two vacuum tubes with their plate and grid circuits; a transformer coupling the plate circuit of the first tube with the grid circuit of the second tube, said grid circuit being grounded; a switch for opening and closing the grid circuit between the secondary of the transformer and the ground; an audio frequency circuit connected with said grid circuit at opposite sides of the switch

and between the secondary of the transformer and the ground; and a variable condenser connected to ground and shunting the said grid circuit, said condenser serving when the switch is closed to tune the grid circuit and when the switch is open as a tone control.

Signed at Toronto, Canada, this 12th day of December, 1930.

10   DUGALD HEPBURN.
                      MILTON L. THOMPSON.
